UNITED STATES PATENT OFFICE.

LIONEL FLEISCHMANN AND AUGUST ELFES, OF BERLIN, GERMANY, ASSIGNEES TO
GENERAL ELECTRIC COMPANY, A CORPORATION OF NEW YORK.

OIL-SWITCH.

1,137,309.

Specification of Letters Patent. Patented Apr. 27, 1915.

Application filed October 11, 1912. Serial No. 725,179.

To all whom it may concern:

Be it known that we, LIONEL FLEISCHMANN, a citizen of the United States, residing at Berlin, Germany, and AUGUST ELFES, 5 a subject of the King of Prussia, residing at Berlin, Germany, have invented certain new and useful Improvements in Oil-Switches, of which the following is a specification.

Our invention relates to oil switches, and 10 has for its object the prevention of the explosions which sometimes occur in oil switches upon the opening of circuits carrying large amounts of energy.

Various devices have been proposed and 15 used to avoid explosions in oil switches. For example, the point of separation of the contacts has been inclosed in a special chamber having strong walls for resisting the explosive action of the arc, this chamber communicating with the body of oil in the tank through a comparatively small opening. Such constructions were developed upon the assumption that the explosion has its origin directly at the arc and is due principally to 20 the direct explosive action of the arc acting below the level of the oil and tending to throw the oil out of the tank. Tests have shown that this is not always the case. The heat of the arc produced in opening the circuit often causes decomposition of the oil 25 and formation of combustible gases, which rise to the surface of the oil in the form of bubbles. Usually this formation of combustible gases occurs without any injurious effect. Sometimes it happens that the arc 30 causes glowing particles of metal or of carbon to be thrown off from the electrodes or from the medium surrounding them. If such glowing particles of metal or carbon 35 encounter the bubbles of combustible gas at the surface of the oil, the explosive mixture formed by the combustible gas and the air above the oil is ignited and an explosion occurs.

40 In accordance with our invention, the occurrence of explosions of oil switches is prevented by making it impossible for the glowing particles to come in contact with the combustible gases at the surface of the oil. We may, for example, accomplish this 45 result by placing above the point of separation of the contacts, partitions of some suitable material which will permit the escape of the bubbles of gas, but will catch and 50 throw back any glowing particles produced

by the arc. One suitable material for such a partition is woven wire netting or similar material having a mesh of such size that the metal or carbon particles are held back, but the gases can go through with but slight resistance. 60

For a better understanding of our invention, reference may be had to the accompanying drawing, in which we have shown, merely for purposes of illustration, one of 65 the many forms in which our invention may be embodied, and in which—

Figure 1 is a longitudinal section of one form of switch embodying our invention; Fig. 2 is a transverse section of the switch 70 shown in Fig. 1; and Fig. 3 is a horizontal section along the line 3—3 of the switch shown in Fig. 1.

In the particular form of switch shown, an oil tank 1 is provided with a suitable 75 cover which supports insulators for two stationary contacts 2, which are submerged in oil.

A bridging contact 3 is mounted to move vertically into and out of engagement with 80 the stationary contacts for the purpose of closing and opening the circuit, as the bridging contact may be moved by any suitable and well known form of actuating mechanism, not shown in the drawing. 85

When the circuit is to be opened, the bridging contact 3 is moved downward, whereupon arcs are formed between the stationary contacts 2 and the bridging contact 3. To prevent these arcs causing severe 90 explosions, we mount above the contacts and beneath the surface of the oil a suitable partition 4, which in the particular form of switch shown in the drawing, is made in the form of a woven wire net work of a suitable 95 mesh. As shown, this partition engages all of the walls of the oil tank 1, consequently nothing can escape from the vicinity of the contacts to the surface of the oil except by passing through the net work 4. This net 100 work is so woven as to offer but little obstruction to the passage of the combustible gases formed by the arc, but the glowing particles of metal or carbon carried upward by the rush of gases cannot easily get 105 through, and will strike against the net work and rebound. As a result of this construction, the glowing particles cannot come into contact with the combustible gases at 110 the surface of the oil, and consequently ex-

plosions at the surface of the oil are prevented.

What we claim as new and desire to secure by Letters Patent of the United States, is,—

- 5 1. An electric switch comprising a vessel containing insulating fluid, coöperating contacts separable in said fluid, and means mounted just below the surface of said fluid for permitting the escape of gases but preventing the passage of heated solid particles from the vicinity of the arc to the surface of said fluid.
- 10 2. An electric switch comprising a vessel containing insulating fluid, coöperating contacts separable in said fluid, and a screen mounted just below and near the surface of said fluid to prevent heated particles from

the vicinity of the arc from rising to the surface of said fluid.

3. An electric switch comprising a vessel 20 containing insulating fluid, coöperating contacts separable beneath the surface of said fluid, and a woven wire screen mounted just below the surface of said fluid to permit the passage of gases but to prevent solid 25 particles from entering the air space above the oil.

In witness whereof, we have hereunto set our hands this 27th day of September, 1912

LIONEL FLEISCHMANN
AUGUST ELFES.
